UNITED STATES PATENT OFFICE.

CHARLES F. L. KING, OF BIRMINGHAM, ENGLAND.

LIFTING-JACK.

1,360,762.

Specification of Letters Patent. Patented Nov. 30, 1920.

Application filed July 7, 1919. Serial No. 309,005.

To all whom it may concern:

Be it known that I, CHARLES FREDERICK LAWRENCE KING, a subject of the King of Great Britain, residing at Birmingham, England, have invented certain new and useful Improvements in Lifting-Jacks, of which the following is a specification.

This invention relates to lifting jacks of the pawl-and-ratchet type and has for its object to provide improved and simplified means for lowering the load.

The invention has more particular reference to jacks in which, for the purpose of lowering, the pawls are alternately thrown out of engagement by trip members carried by a rocker or movable member which is adapted to be secured in an inoperative position, when the trip members have no effect on the pawls, for the purpose of lifting.

According to the present invention the rocker is adapted to be locked or held in an operative position for lowering, as well as in an inoperative position for lifting, and carries trip members in the form of spring-actuated levers or angularly moving parts.

The trip members, when in operative position, are arranged so that as such pawl descends the corresponding trip member moves it out of engagement while the other pawl moves into engagement but said disengaged pawl engages with another tooth when again lifted. In the case of a single-acting jack having one lifting pawl coöoperating with a retaining pawl, the trip member for throwing out the latter is arranged to be operated by the raising of the lifting pawl as the latter moves into engagement. The pawls are arranged to be taken into engagement by springs which are weaker than, and adapted to be overpowered by the trip springs.

Figure 1 of the accompanying drawings is a side elevation of a double-acting jack constructed in accordance with the present invention, the front cover-plate being removed, and the trip levers being in their inoperative position to allow the jack being used for lifting.

Fig. 2 is a cross-section on line z , Fig. 1.

Fig. 3 is a vertical section showing the lifting pawls in engagement with the rack.

Fig. 4 shows the rocker plate held in the position in which the trip levers are operative upon the lifting pawls, so as to allow of the load being lowered. This view shows the handle in the raised position, and the load supported by the upper pawl.

Fig. 5 is a similar view, but shows the handle in the lowered position, and the load supported by the bottom pawl.

Fig. 6 represents a side elevation of a single-acting jack constructed in accordance with this invention.

Fig. 7 shows a further modification.

Referring to the double-acting jack shown in Figs. 1 to 5, operating lever 1 is fulcrumed at 2 within a casing 3 carried by the fixed frame 4 of the jack, and has two pawls 5, 6, pivoted to it upon opposite sides of the fulcrum, so that as the lever is oscillated in a vertical plane the one pawl moves upward and the other downward. The said pawls engage with a ratchet toothed rack 7 upon the lifting pillar 8 of the jack, and are kept in engagement therewith by means of light springs 9, 10, (see Fig. 3) which cause the pawls, as they descend, to wipe over the teeth in order to engage a lower tooth and support the load as each stroke is completed. Thus, the load is raised by the outer pawl 5 when the lever is lifted and by the inner pawl 6 when the lever is depressed.

To enable the load to be lowered, each pawl carries a laterally projecting pin 11, 12, and beneath these pins are trip levers 13, 14, both levers being pivoted, at one end, to a rocker plate or arm 15 pivotally mounted at its lower end, as at 16. The trip levers 13, 14, are acted upon by springs 17, 18, which tend to force them upward against stops 19, 20, upon the said rocker. The latter is adapted to be held in one or other of two angular positions by means of a pivoted detent or catch comprising a lever 21 extending through a slot in the side of the casing and having a nose 22 which, in the lifting position of the trip levers, engages beneath a tooth or projection 23 on the rocker 15, as shown in Fig. 1. To place the trip levers in a position to permit of lowering, the outer end of the detent 21 is pressed downward, causing the inner end to move upward and swing over the rocker into the position shown in Figs. 4 and 5, said rocker being retained in this position by the nose 22 of the detent engaging behind the shoulder of the tooth 23, as shown.

In this position the pawls are raised into the position shown, with their upwardly inclined nose ends immediately beneath the pins 11, 12 on the pawls. When the operating lever 1 is raised as in Fig. 4, the inner pawl 6 is in the lowered position and its

pin 12 is engaged and acted upon by the lever 14, so that the said pawl is held out of engagement with the rack, while the load is supported by the outer or upper pawl 5. 5 On depressing the operating lever, the load is lowered due to the descent of the said pawl 5, whose lateral pin 11 moves into engagement with the edge of the trip lever 13, which it slightly depresses.

10 The pin 11 continues to move parallel to the rack while the pawl 5 is under load, until the inner pawl 6, which, during this movement, has been raised, is taken by its spring into engagement with a tooth of the 15 rack, and supports the load, when the spring 17 acts so as to throw the upper pawl 5 completely out of engagement, as in Fig. 5. The load being now taken by the inner pawl, the operating lever is raised, causing 20 the said pawl to be lowered and to engage with trip lever 14 and compress its spring, which acts to throw the said pawl out of engagement with the rack immediately the 25 upper pawl 5 moves into engagement and takes the load, as in Fig. 4.

Instead of the trip members consisting of pivoted arms acted upon by springs, they may consist of plain wire springs or of leaf springs carrying bosses or raised parts at 30 the ends.

In the case of a single-acting jack, such as shown in Fig. 6, having a retaining pawl 24 for holding the load while the lifting pawl 6 is withdrawn, a trip lever 14 (shown 35 as a pivoted leaf spring) is employed in connection with said lifting pawl. Between the latter and the retaining pawl 24, however, a double-armed leaf or wire spring 25 is employed mounted upon the rocker 15 40 which carries the lower trip lever 14. If the detent 21 is depressed so as to move the rocker 15 into the lowering position, then as the lifting pawl 6 is raised to engage the rack 7, its lateral pin 12 engages the lower 45 arm of said double-armed spring, moving the upper arm into engagement with a lateral pin 11 on the retaining pawl. The arms of the spring are thus pressed together until the pressure upon the pin 11 is sufficient to throw the retaining pawl out of 50 engagement. The load is then lowered by the pawl 6, until the latter is thrown out of engagement by the trip lever 14, prior to which the retaining pawl 24 will have 55 reengaged the rack due to the pressure of the spring 25 being relieved due to the descent of the lifting pawl.

In the modification represented in Fig. 7, which shows a double-acting jack, the trip 60 members 13, 14, consist of arms rigidly carried upon a lever 26 pivoted at 27 to the rocker 15 which is pivoted at 16 and held in either of two positions by the detent 21, as in Figs. 1 to 5. The arms or trip members

13, 14, are influenced by the spring 28 65 pressing upon the stud 29 of the lower arm 14. The studs 11, 12, on the pawls 5, 6, engage with the trip arms 13, 14, as in the previous arrangement.

Having fully described my invention, 70 what I desire to claim and secure by Letters Patent is:—

1. A lifting jack comprising pawl-and-ratchet lifting mechanism, an operating lever, a rocker carrying relatively angularly-movable spring-actuated trip members 75 adapted to coöperate with the lifting pawls, means for locking the rocker in an inoperative position where the trip members have no effect upon the pawls, and means for locking the rocker in an operative position for lowering, in which the trip members take a position such that they act upon the pawls, as the latter are lowered, so as to throw said pawls out of engagement. 80

2. A lifting jack comprising a ratchet-toothed rack, an operating lever, pawls carried by the lever, a rocker carrying spring-actuated trip levers pivoted thereon, stops 90 on the rocker against which the trip levers are maintained, means for locking the rocker in an inoperative position where the trip levers have no effect upon the pawls, and means for locking the rocker in an operative 95 position for lowering so that the trip levers are engaged by the pawls, as the latter descend, and cause said pawls to be thrown out of engagement with the rack.

3. A double-acting lifting jack comprising a ratchet-toothed rack, an operating lever, two lifting pawls carried by the lever and coöperating with the rack, a rocker carrying two spring-actuated trip levers 100 pivoted thereon for coöperating with the respective pawls, means for locking the rocker 105 in an inoperative position where the trip levers have no effect upon the pawls, and means for locking the rocker in an operative position for lowering, the one pawl, as it descends, being moved out of engagement by 110 its trip member while the other pawl, in rising, moves into engagement with the rack, said disengaged pawl engaging with another tooth when again lifted.

4. A lifting jack comprising pawl and ratchet lifting mechanism, an operating lever, a rocker carrying relatively angularly movable spring actuated trip members 115 adapted to coöperate with the lifting pawls, and a pivoted locking lever coöperating with a projection on the rocker in order to lock the latter in a position for lowering the load. 120

In testimony whereof I have hereunto set my hand in presence of a subscribing witness.

C. F. L. KING.
